UNITED STATES PATENT OFFICE

153,426

DESIGN FOR A FLOATING TOY

Peter Ganine, Los Angeles, Calif.

Application January 16, 1948, Serial No. 143,832

Term of patent 14 years

(Cl. D34—2)

To all whom it may concern:

Be it known that I, Peter Ganine, a citizen of the United States, residing at Los Angeles, in the county of Los Angeles and State of California, have invented a new, original, and ornamental Design for a Floating Toy, of which the following is a specification, reference being had to the accompanying drawing, forming part thereof, in which:

Fig. 1 is a perspective view of a floating toy, showing my new design;

Fig. 2 is a side elevational view; and

Fig. 3 is a bottom plan view thereof.

I claim:

The ornamental design for a floating toy, as shown.

PETER GANINE.
